UNITED STATES PATENT OFFICE.

ARMAND MAYER, OF LEVALLOIS-PERRET, FRANCE.

DEVICE FOR DRIVING THE HANDS OF MONUMENTAL CLOCKS.

Application filed December 16, 1922. Serial No. 607,403.

To all whom it may concern:

Be it known that I, ARMAND MAYER, a citizen of the French Republic, residing at Levallois-Perret, France, have invented certain new and useful Improvements in Devices for Driving the Hands of Monumental Clocks (for which I have filed an application for patent in France on the 17th December 1921), of which the following is a specification.

Turret clocks have become known comprising auxiliary movements and contact devices, which when the electric current fails, effects automatically the readjusting of the hand mechanism. In the arrangements of known type contacts are used which rotate with the hands which is however undesirable, as, when the working current fails, the contact giving fails also.

This invention has for its object to avoid this inconvenience.

The invention consists in connecting with one another the hands of the turret clock and the auxiliary movement by means of a differential gear designed to close the circuit of a motor, which drives the hands of the turret clock, as soon as there is no longer synchronism between the auxiliary movement and the hands of the turret clock.

In order to make the invention fully understood I shall hereafter proceed to describe the same with reference to the form of construction shown by way of example on the accompanying drawing, wherein:

Fig. 1 shows in section the arrangement according to the invention.

Fig. 2 is a plan view of Fig. 1.

The auxiliary movement 1 and the axle 2 of the dial train drive each a bevel wheel 3 of the planet wheels 6 and 7 of which revolve around the shaft 8 fixed in the supporting frame 9 of the planet wheel rotatably mounted on axle 2.

A gear wheel 10 rigidly fixed on the supporting frame 9 drives a spur wheel 12 through the intermediary of a toothed wheel transmission 11. The ratio of transmission of this gear is selected so that the supporting frame 9 of the planet wheels executes six revolutions when the spur wheel 12 completes one revolution.

On the supporting frame 9 of the planet wheels a notched disk 13 and on the spur wheel 12 a notched disk 14 is arranged. Rollers 15 and 16 bear against the periph-

eries of said notched disks 13, 14, respectively. These rollers 15, 16 are mounted on arms 17, 18 fixed at the ends of the hollow shaft 19. On this hollow shaft 19 a lever 20 is further fixed into the end of which a screw 21 is screwed adapted to come in touch with a counterscrew 22 when one of the rollers 15, 16 is being raised.

The circuit 24 is closed across the motor 23 as soon as the contact between the screws 21 and 22 is closed. This hand train is driven from the motor 23 for instance by means of a worm 25 and worm wheel 26. The remaining part of the mechanism is not illustrated as it is generally known. The motor 23 may evidently serve for normally driving the hand of a turret clock.

The operation of the mechanism is as follows:

At the normal working the two bevel wheels 3 and 4 revolve synchronously but in inverse directions. The supporting frame 9 of the planet wheels remains stationary and as the rollers 15, 16 are in engagement with the notches of disks 13, 14 the contact at 21, 22 is interrupted so that the mechanism cannot operate. As soon as the current in the circuit fails, the hands of the turret clock will stop, the hands of the auxiliary movement continuing to rotate. As the bevel wheel 4 is stopped but wheel 3 continues to rotate the supporting frame 9 or the planet wheels must rotate at a speed which is equal to half the speed at which the wheel 3 revolves. The supporting frame 9 will therefore execute one rotation in two hours. Owing to the transmission gear 10, 11, 12 the second disk 14 revolves also but executes one revolution in 12 hours.

Herefrom results that, as soon as a sufficiently great angular difference exists between the two pairs of hands, the roller 15, which is disengaged from the notch of disk 13, permanently closes the circuit of the motor on the main line so that as soon as the current begins to flow again through the main line the motor is started and the hands of the turret clock rotate rapidly. At the same time the bevel wheel 4 of the differential gear rotates the supporting frame 9 of the planet wheels in the opposite direction. The motor will therefore be stopped again only when the rollers 15, 16 have again come in engagement with the notches of disks 13, 14, e. g. when the hands of the turret clock synchronize with those of the auxiliary

movement. As two disks (13 and 14) are provided the synchronization is ensured for the hour hand as well as for the minute hand.

5 The same will be the case if the angular difference between the hands of the turret clock and those of the auxiliary movement increases beyond a predetermined value either owing to an accidental failing of the 10 current, caused for instance by snow, or owing to the failing of the normal movement.

I claim:—

1. A driving mechanism for the hands of turret clocks comprising in combination with the hand mechanism, an electro-motor in gear with said hand mechanism, an auxiliary clockwork movement, a differential gear connecting said auxiliary movement with said hand driving mechanism, a reducing 20 gear for recording the revolutions of the central element of said differential gear, a source of electric current connected with said electro-motor, and a set of contacts controlled by said central element of said differential gear closing the circuit of the motor with said source of current and interrupting said circuit only when the indications of the turret clock and of the auxil-

iary clockwork movement are in synchronism.

2. A driving mechanism for the hands of turret clocks comprising in combination with the hand mechanism, a motor for driving said mechanism, an auxiliary mechanism, a contact device for automatically adjusting the hand mechanism when the current fails, a differential gear connecting said auxiliary movement and said hand mechanism, two notched disks one for the hour hand and the other for the minute hand 40 connected with the differential gear, rollers bearing against the rims of said notched disks, levers carrying said rollers and designed to act upon the contacts of said contact mechanism in such a manner that the 45 circuit for said motor driving the hands is cut only when the hands of the turret clock and those of the auxiliary movement are in synchronism.

In testimony whereof I affix my signature 50 in presence of two witnesses.

ARMAND MAYER.
